BURNER CONTROL FOR REVERSING FURNACES

Claude J. Geisel, Elyria, and Peer D. Nielsen,
Lorain, Ohio, assignors to National Tube Company, a corporation of New Jersey

Application September 3, 1940, Serial No. 355,226

2 Claims. (Cl. 158—36)

This invention relates to burner controls for reversing furnaces, and more particularly to those which are used on open hearth furnaces in the manufacture of steel, although not limited thereto.

In open hearth furnace practice, a combustion sustaining mixture of fuel and air is introduced through a port on one side of the furnace and the products of combustion are withdrawn therefrom through a port on the other side thereof, and from time to time the operation is reversed, the port initially serving as the intake port becoming the exhaust port and vice versa.

It is the usual practice to locate the fuel shut-off and reversing valves at a reversing stand positioned at a substantial distance from the burners which they control. When liquid fuel is used, such as oil or tar, there is a considerable quantity thereof left in the line between the valve and the burner and this often increases in temperature after the valve has been closed due to the proximity of the feed line to the highly heated furnace and the accessories thereof. Frequently the fuel feed line is enclosed with a steam line in an insulated wrapper to assist in the heating of the oil or tar previous to atomization, and when the flow of fuel ceases due to the furnace reversal, an increase in the fuel temperature is bound to occur. The liquid fuel remaining in the idle fuel feed line expands with increased temperature and is partially lost through the open end of the line at the fuel burner. Fuel issuing from the burner in this manner burns, but for no useful purpose, and causes objectionable smoking in the furnace as no air is provided for its combustion. This condition causes clogging of the burner due to the formation of the deposit at its open end.

According to the most prevalent practice, the controls for reversing the furnace are located at a central point as otherwise the reversal of the furnace could only be accomplished by workmen walking to the required locations. Such centralization of the reversing controls at a remote point gives rise to numerous difficulties; and frequently manual control immediately ahead of each burner is resorted to when a reversal of direction of firing is desired.

Another prior art practice includes the simultaneous closing of one valve with the opening of the other, accomplished with the utilization of the atomizing steam pressure as a means for operating the valves for the liquid fuel. Such practice is not desirable for reasons which will appear more fully hereinafter and we have,

therefore, sought to avoid the simultaneous interrupting flow of fuel to one burner and initiation of flow to the other in coordination with the operation of interrupting the steam flow to one burner and initiating the steam flow to the other.

It is among the objects of the present invention to provide a reliable and efficient reversing control for fuel burners.

Another object is to provide a system of the class described which is so constructed and arranged as to require the elapse of an interval of time between the interruption of flow of fuel to one burner and its initiation to the other, together with the purging of the burners with steam or other fluid both before and after the application thereto of the liquid fuel.

Another object is to provide a system of the class described with the controls located at a remote point and so constructed and arranged as to provide for selective operation of the valves.

The foregoing and other objects will be apparent after referring to the drawing, in which:

Figure 1 is a diagrammatic view of the fuel apparatus of a furnace provided with apparatus embodying the teachings of the present invention;

Figure 2 is a view partly in side elevation and partly in section of one of the fuel valves of the apparatus of the present invention; and

Figure 3 is a diagrammatic view of additional apparatus to be used in conjunction with the apparatus of Figure 1.

Referring more particularly to the drawing, the numeral 2 generally designates an open hearth furnace provided on either side with a liquid fuel burner, as at 4 and 5. As stated hereinbefore, it is old in the art to position burners in these locations and provide them with liquid fuel through suitable fuel feed supply pipes as designated at 6 and 7, controlled from a remotely disposed control station 9. In order to atomize the fuel fed through the supply lines 6 and 7, steam is furnished to the burners 4 and 5 through suitable pipes, respectively designated at 11 and 12. Within each of the steam pipes 11 and 12 and at points adjacent the burners 4 and 5, there is a solenoid operated valve, as at 13 and 14, the latter being controlled through suitable electric circuits 16 and 17 from the control station 9. It is additionally old in the art to provide within the fuel feed supply pipes 6 and 7, and adjacent to the burners 4 and 5, suitable pressure operated valves designated hereinafter at 20 and 21 and connected to and operated by the steam supply pipes 11 and 12. Prior to the

present invention, the foregoing combination of elements was so arranged and operated one with respect to the other that the atomizing agent (i. e., steam), is used to open fuel valves immediately in back of the burners.

According to the teachings of the present invention, there is provided at the locations designated hereinbefore at 20 and 21, valves operated by the pressure from the steam pipes 11 and 12. Each of the valves 20 or 21 comprises a valve body 200, see Figure 3, provided with an oil inlet port 201 which communicates with a chamber 202, from which the oil is permitted to flow through a restricted orifice 203 into a smaller chamber 204. From the small chamber 204 the oil issues through a port 205 to be fed to the burners designated hereinbefore at 4 and 5. Through the restricted orifice 203 there extends a valve stem 210 which projects through a packing gland 211 at the top of the valve body 200. Within the chamber 202 the valve stem 210 carries a valve generally designated at 213. This valve 213 carries a valve seat 214 which is adapted to seat against a similar valve seat 215 which is carried in the restricted orifice 203. In parallelism with the valve stem 210 the valve body 200 is provided with a cylindrical chamber 220 in which there is disposed a piston 221, the latter being movable upwardly by means of steam admitted through a port 223 in the bottom of the valve body 200. The top of the piston 221 is provided with a valve seat 225 which is adapted to seat against a valve seat 226 in a restricted aperture 227 which communicates with a chamber 229 of smaller diameter than the cylindrical chamber 220. The chamber 229 carries a coil spring 230 which extends through the restricted aperture 227 and seats in a recess 231 in the top of the piston 221. Secured to the top of the piston 221 is a shaft 232 which projects through an opening 233 in the top of the valve body 200. Pivots connected to the top of the shaft 232 is one end of a link 240 which is, on its other end, pivotally connected to the top of the valve stem 210. At a position closely adjacent the valve stem 210 the link 240 is pivotally connected to a post 242 which is integrally formed on the top of the valve body 200, the mechanical advantage afforded thereby being in the ratio of 2½ to 1. By providing at the points designated 20 and 21, a valve body 200 and associated instrumentalities, and connecting the respective steam supply pipes 11 and 12 to the ports 223, the liquid fuel feed supply pipes 6 and 7 to the ports 201, and the fuel burners 4 and 5 to the ports 205, there is provided a system which operates in the following manner:

Assuming the burner 4 to be in operation and the burner 5 to be idle, the operator reverses the furnace by operating the switch 18 in the electrical line 16 to close the solenoid operated valve 13 thereby cutting off the supply of steam coming through the pipe 11. When the pressure of the steam remaining in the pipes beyond the valve 13 drops sufficiently, the spring 230 in the valve body 200 operating against the pressure of the steam coming through the port 223 presses the piston 221 downwardly. The downward movement of the piston 221 moves with it the integral shaft 232 and that end of the link 240 which is pivotally connected to the top of the latter. Through the mechanical advantage of 2½ to 1, the valve stem 210 is raised, thereby moving into contact the valve seat 214 on the valve 213 with the valve seat 215 carried in the restricted orifice 203. The closing of the valve 213 cuts off the

flow of oil issuing from the port 205. After the oil valve closes, the burner 4 is automatically purged by the expansion and dissipation of steam remaining in the pipe 11.

5 In order to set in operation the burner 5, the operator closes the switch 19, which opens the solenoid operated valve 14, thus admitting steam to the burner 15 to thereby purge the burner 5 prior to the application of fuel. As soon as the 10 back pressure of steam in the pipe 12 builds up slightly, it overcomes the force of the spring 230 which, in a manner reverse to that described in conjunction with the discontinuing of burner 4, opens the valve 213 and admits oil from the port 201 to the chamber 202, restricted orifice 203, chamber 204 through the oil outlet port 205 to the burner 5.

From the foregoing, it will be observed that the valves 200, disposed at the locations 20 and 21 in Figure 1, are opened by the application of atomizing steam and are closed by means of springs 230 when the atomizing steam is shut off. The springs 230 are, of course, made to resist the steam pressure desired under the minimum pressure required for atomization.

25 Referring more particularly to Figure 3, there is provided in each of the steam supply pipes 11 and 12 a lubricating oil trap 250 for each of the valves 20 and 21. These oil traps 250 serve the joint purpose of lubricating the pistons 221 and their respective valves and also to prevent steam coming into contact therewith. Preferably both of the pistons 221 are provided with oil grooves to prevent the escape of oil past the pistons 221 before the valve seats 225 and 226 are closed.

30 A vent (not shown) is provided in each of the cylindrical chambers 220 to permit the escape of air or seepage and to prevent equalization of pressure above and below the pistons 221.

35 By using the atomizing agent (i. e., steam) as the operating media of the valves 200, the proper manipulation of the atomizing agent and liquid fuel, with respect to the proper sequence of application and removal, is absolutely assured.

40 Referring again to Figure 3, it will be perceived that on its way from the port 205 to the burners 4 or 5, the oil flows to and through an atomizer 251. In addition, in each of the steam supply pipes 11 and 12 there is provided a steam chamber 252. These steam chambers 252 are disposed between the lubricating oil traps 250 and the atomizers 251. By employing atomizers in advance of the burners and atomizing steam chambers 252 which constitute enlargements of the 45 steam supply pipes 11 and 12 the purging of the burners may be increased.

50 The lubricating oil traps 250 can be made of any size to effect the desired purging before and after the application to shut off respectively the liquid fuel and also serve as a reservoir for the atomizing agent (i. e., steam).

55 While we have shown and described one specific embodiment of the present invention, it will be seen that we do not wish to be limited exactly thereto, since various modifications may be made without departing from the scope of the invention, as defined by the following claims.

We claim:

60 1. A burner control comprising a plurality of fuel burners, a pipe for supplying liquid fuel to each of said fuel burners, a valve in each of said pipes, said valves being disposed adjacent the fuel burners they control, a conduit arranged to deliver fluid under pressure for atomizing the 65 fuel supplied to each of said burners, a valve-

operating means organized with each of said valves, said means comprising chests severally communicating with said conduits and including valve-shifting members movable between alternate positions upon changing from one to the other of alternate conditions of pressure in said conduits, a remote control station including control means operable for selectively controlling the supply of fluid under pressure to each of said conduits and thereby effecting the individual operation of said valve-operating means, said burners being purged by said atomizing fluid upon changing the pressure condition in said conduits, and means for delaying the movement of said shifting members upon supplying atomizing fluid to said conduits until the said fluid purges said burners, each of said conduits including an enlargement whereby purging of the burners is increased.

2. A burner control comprising a plurality of fuel burners, a pipe for supplying liquid fuel to each of said fuel burners, a valve in each of said pipes, said valves being disposed adjacent the fuel burner they control, a conduit arranged to deliver fluid under pressure for atomizing the 25

fuel supplied to each of said burners, a valve-operating means organized with each of said valves, said means comprising chests severally communicating with said conduits and including 5 valve-shifting members movable between alternate positions upon changing from one to the other of alternate conditions of pressure in said conduits, a valve in each of said conduits, said last-named valves being disposed adjacent the 10 fuel burners aforesaid, a remote control station including control means operable for selectively operating said last-named valves to control the supply of fluid under pressure to said conduits and thereby effect the individual operation of 15 said valve-operating means, said burners being purged by said atomizing fluid upon changing the pressure condition in said conduits, and means for delaying the movement of said shifting members upon supplying atomizing fluid to said conduits until the said fluid purges said burners, each of said conduits including an enlargement whereby purging of the burners is increased.
